UNITED STATES PATENT OFFICE.

WILLIAM C. BRIDGES, OF PHILADELPHIA, PENNSYLVANIA.

IMPROVEMENT IN OPTICAL TELEGRAPHS.

Specification forming part of Letters Patent No. 34,127, dated January 14, 1862.

To all whom it may concern:

Be it known that I, WILLIAM C. BRIDGES, of Philadelphia, Pennsylvania, have invented an Instrument for Transmitting Messages; and I do hereby declare the following to be a full, clear, and exact description of the same, reference being had to the accompanying drawings, and to the letters of reference marked thereon.

My invention consists of a tube with a lens, and one or more adjustable mirrors arranged, substantially as explained hereinafter, in combination with the devices hereinafter described, or their equivalents, for obscuring and exposing the lens, (the latter being illuminated by the rays of the sun reflected from the mirrors,) or for moving differently-colored plates of glass to the front of and away from the lens, so that on observing the latter from a distance its exposure and obscuration or the different colors seen will be the means of informing the observer of the nature of the messages transmitted by the operator.

In order to enable others to make and use my invention, I will now proceed to describe its construction and operation.

On reference to the accompanying drawings, which form a part of this specification, Figure 1 is a side view of my instrument for transmitting messages; Fig. 2, a plan view; Fig. 3, an end view looking in the direction of the arrow, Fig. 2; and Fig. 4, a diagram illustrating a modification of part of the instrument.

Similar letters refer to similar parts throughout the several views.

A is the base of the instrument, and to this base is attached a tube B, at the rear of which is secured a lens.

To a bracket a on the base is hinged a lever having two arms C and D, on the outer end of the former of which is a disk d of a diameter as large as or somewhat larger than the tube B, one end of a spiral spring b being connected to the short arm D of the lever, and the other end to a pin c secured to the base, and the tendency of this spring being to retain the disk in the elevated position (shown in Fig. 3) from which point it cannot be raised owing to the arm D bearing against a pin projecting from the bracket a.

On the long arm C of the lever is a project-

ing plate e of proper dimensions for receiving the finger of the operator. In front of this lever and its disk d is another disk E so hinged to the base that it can be elevated at right angles to the same or depressed so as to be in contact with the base, as shown by dotted lines, Fig. 2, this disk having in its upper edge a notch d corresponding with a notch in a flange d' at the rear of the tube B, and these notches being so situated that a line x drawn from the bottom of one notch to that of the other shall be parallel with a line drawn through the center of the tube.

At the rear of the tube is a frame to which is hung a circular mirror F, this frame being so connected to the base A as to be readily turned thereon, and the mirror being so hung to the frame that it may be moved to any desired angle. A similar mirror G hung to a similar frame may be connected to the base at the point shown in Fig. 2, or at any other point which may be the most advantageous position for the mirror to receive the direct rays of the sun.

It should be understood that in using the above-described instrument for transmitting messages it has in the first instance to be so adjusted that the tube may be directed accurately to the point where the observer who has to receive the messages is situated, the lens of the tube being directly within the line of the observer's vision. In order to adjust the instrument to this position, the disk E is first raised to the vertical position shown in Fig. 1, after which the operator, looking toward the notch in the flange of the tube B, adjusts the instrument to such a position that the point to which he desires to direct the instrument, the bottom of the notch on the disk E, and the bottom of the notch in the flange shall all be in the same line x of vision.

It will be understood that in order to facilitate the adjustment of the instrument it should be attached to a tripod by means of a ball-and-socket joint and other appliances similar to those used in connection with theodolites and other like instruments.

When messages have to be delivered from a great distance, a telescope should be connected to the instrument, care being taken that the telescope is placed parallel with the tube B. In this case the notch in disk E is

dispensed with, the adjustment of the instrument being regulated by the telescope.

The position of the mirrors F and G will depend upon the direction of the rays of light from the sun in respect to the position of the instrument, the mirror G being so adjusted as to receive the direct rays which are reflected onto the mirror F, and thence directed onto the lens, which becomes so brilliantly illuminated as to be plainly visible from a distance of twenty-five miles with the aid of a telescope.

In adjusting the mirror G the focus of the lens illuminated by the light reflected from the mirror should coincide with a small hole in the elevated disk E, a line drawn through this hole and through the center of the tube being parallel with the line α drawn from the notch of the disk to the notch of the flange. If care is not taken to thus adjust the mirror G, it will not be fully illuminated.

In some instances the mirror G may be dispensed with, as when the instrument is so situated that the rays of the sun are received directly by the mirror F.

In order to impart greater brilliancy to the lens, a concave instead of a plain mirror may be used at the rear of the tube, as seen in Fig. 4, the rays from this mirror being concentrated in the lens.

The messages are delivered by the movements of the disk d , which may be depressed so as to cover the end of the tube B or be allowed to rise by the action of the spring b to the position shown in Fig. 3, when the end of the tube is exposed. This obscuring and exposing of the illuminated lens will be clearly seen by the observer either by the naked eye if the distance be short, or by the aid of a telescope if the distance be long. The operator may move the disk d precisely in the same manner as though he handled the signal-key of an ordinary Morse telegraphing-instrument, and the observer who has to interpret the signals must be guided by the length of

time during which the lens remains obscured and by the rapidity of the movements of the disk precisely as he would be guided by the ticks of a telegraph-instrument. In some cases it may be advisable to discard the Morse alphabet and to make use of a secret system of signals predetermined by the operators. A system of signals and messages may also be transmitted by using a number of disks d , any one of which may be operated independently of the others, each disk carrying a plate of glass different in color from that of the other disks, so that the operator can bring any one of the differently-colored disks opposite to the illuminated lens, the observer in interpreting the messages being guided by the colors presented.

When the instrument has to be used during the night, a lamp may be so placed between the concave mirror and the lens that the rays of light will be reflected by the mirror onto the lens, thereby brilliantly illuminating the latter.

I wish it to be understood that I do not desire to claim, broadly, transmitting messages between distant points by exposing and obscuring a luminous or illuminated object, but that I limit my claim to and desire to secure Letters Patent for—

The tube B with its lens and one or more adjustable mirrors arranged substantially as described, in combination with the device herein described or any equivalent to the same for obscuring or exposing the lens or moving differently-colored plates of glass to the front of and away from the lens, as set forth, for the purpose specified.

In testimony whereof I have signed my name to this specification in the presence of two subscribing witnesses.

W. C. BRIDGES.
